(57) **CLAIM**

The ornamental design for a fastening clip for cables, as shown and described.

DESCRIPTION

FIG. 1 is a perspective view of a first embodiment of a fastening clip for cables showing the new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof;

FIG. 8 is a bottom plan view thereof;

FIG. 9 is a perspective view of the first embodiment of the fastening clip for cables in an open position;

FIG. 10 is a perspective view of a second embodiment of the fastening clip for cables showing the new design;

FIG. 11 is another perspective view thereof;

FIG. 12 is a front elevation view thereof;

FIG. 13 is a back elevation view thereof;

FIG. 14 is a left-side view thereof;

FIG. 15 is a right-side view thereof;

FIG. 16 is a top plan view thereof;

FIG. 17 is a bottom plan view thereof; and,

FIG. 18 is a perspective view of the second embodiment of the fastening clip for cables in an open position.

The broken lines depict portions of the fastening clip for cables that form no part of the claimed design.
